UNITED STATES PATENT OFFICE

101,999

DESIGN FOR A COASTER BRAKE

Alvin J. Musselman, Cleveland Heights, Ohio

Application August 4, 1936, Serial No. 64,235

Term of patent 14 years

To all whom it may concern:

Be it known that I, Alvin J. Musselman, a citizen of the United States, residing at Cleveland Heights, in the county of Cuyahoga and State of Ohio, have invented a new, original, and ornamental Design for a Coaster Brake, of which the following is a specification, reference being had to the accompanying drawing forming a part thereof, in which the single figure is an elevational view of a coaster brake embodying my new design.

The brake as herein illustrated is intended primarily for bicycles, and comprises a hub shell, the cylindrical surface of which is broken up by a series of annular ribs in two groups symmetrically arranged with respect to a central plane transverse to the axis of the hub.

I claim:

The ornamental design for a coaster brake, substantially as shown and described.

ALVIN J. MUSSELMAN.
